Williams & Pitchard

UNITED STATES PATENT OFFICE.

CLIFFORD KIRBY MACDONALD, OF BROCKTON, MASSACHUSETTS.

SHOE LAST.

Application filed August 14, 1922. Serial No. 581,587.

To all whom it may concern:

Be it known that I, CLIFFORD KIRBY MACDONALD, a citizen of the United States, and resident of Brockton, Plymouth County,

5 State of Massachusetts, have invented certain new and useful Improvements in Shoe Lasts, of which the following is a specification.

This invention relates to lasts adapted to 10 be used in the manufacture of shoes and has particular reference to that class of last in which the toe part is hingedly connected to the heel portion so that the two sections may be moved with respect to each other in 15 order that the last as a whole may be easily inserted into or withdrawn from a shoe.

An important object of the invention is 20 to generally improve the various elements entering into the last embodying my invention, the improvements being directed particularly to the hinge mechanism by which the toe and heel sections are connected together, with a view of reducing the cost of production of the last and facilitating the 25 assembly of the several component parts thereof.

Other objects and certain advantages of 30 the invention will become apparent from the following description when taken in connection with the accompanying drawings, in which—

Figure 1 is a plan view of a last embodying my invention.

Figure 2 is a side elevation of the last 35 shown in Figure 1, a portion of the same being broken away to show the positions of the several hinge elements when the last is extended.

Figure 3 is a view similar to that of Figure 2, a portion of the last being broken away to show the positions of the several hinge elements when the last is broken or collapsed.

In the drawings, wherein is shown what I 45 at present consider the preferred form of my invention, the numeral 5 indicates a heel portion, which is, at its forward end, tapered rearwardly and provided with a transversely disposed lug or offset portion 6. 50 This lug is preferably formed integral with the heel portion 5, and is adapted to coop-

erate with a toe section 7, which is cut away at its rear end to provide a groove or seat 8, into which the lug 6 is adapted to fit and operate.

As a means for hingedly connecting the heel portion 5 to the toe section 7 I employ an improved form of hinge 9, which comprises hinge members 10 and 11. The hinge member 10 includes a shank 12, which is 60 fitted within an opening 13, formed in the heel portion 5, and an angularly disposed arm 14, adapted to operate within an opening 15 formed in the toe section 7. In order to retain the hinge member 10 correctly positioned with respect to the heel portion 5, I employ a transversely disposed pin 16, which is passed through the heel portion 5 and an opening 17 formed in the end of the shank 12. The hinge member 11 is adapted to co- 65 operate with the arm 14, as will hereinafter more particularly appear, and comprises a pair of plates 18 constructed from suitable resilient metal. These plates include extensions 19, which are formed integral with 70 resilient wing members 20, the extensions 19 being fitted within an opening 21, formed in the toe section 7, whereas the wing members 20 are accommodated within the opening 15. In order to maintain the hinge member 11 75 in a correct position with respect to the toe section 7, I employ a transversely disposed pin 22, which is passed through the toe section 7 and aligned openings 23 formed in the ends of the extensions 19.

For the purpose of pivotally connecting the hinge members 10 and 11 together, I employ a tubular rivet 24, which is passed through the plates 18 adjacent the wing members 20, and the shank 12 adjacent the 80 angularly disposed arm 14. By employing the tubular rivet 24, I am enabled to readily accommodate a transversely disposed centering and reinforcing pin 25, which is passed through the transversely disposed lug 6 and 85 the hinge members 10 and 11, at their point of pivotal connection. Not only does this pin lend rigidity to the hinge as a unit and tend to retain the hinge members 10 and 11 in their proper positions with respect to the 90 heel portion 5 and toe section 7, respectively, but it also enables me to definitely and prop-

erly position the center of the hinge with respect to the heel portion 5 and toe section 7 in assembling the last, and thereafter retain the pivotal point of the hinge members 5 10 and 11 in proper positions with respect to the heel portion 5 and toe section 7 to insure an accurate operation of these members without danger of binding therebetween.

10 With lasts of the type to which my invention is directed, it is customary to provide a means for locking the heel and toe sections in their extended positions, and to accomplish this locking effect I provide the 15 angularly disposed arm 14 with a transverse opening 26, into which is fitted a steel ball 27, adapted to enter a somewhat similar opening or pocket 28, formed in one of the wing members 20, when the toe section 7 is 20 extended with respect to the heel portion 5, as shown in Figure 2. When the toe section 7 is moved from its position shown in Figure 2 to the position shown in Figure 3, the ball 27, upon being dislodged from the opening 28, exerts opposing thrusts upon the wing 25 members 20, which yield slightly, due to their inherent resiliency. After the toe section 7 has moved a predetermined distance, the ball 27 is permitted to enter an elongated slot or pocket 29 formed in one of the wing members 20 after which further movement of the toe section is readily permitted.

It might be well to mention that while I have described both of the plates 18 as being 35 resiliency, in some cases if desired only one of these plates need be such, and that in some instances the opening 28 and elongated slot 29 may be both formed in the same wing number 20.

40 Since the angularly disposed arm 14 is adapted to operate between the two wing members 20, and since the ball 27 is of such a size as to cause a slight lateral separation of the wing members 20 when the same is 45 dislodged from the elongated slot 29, due to the movement of the toe section 7, from its collapsed position to its extended position, it follows that the ball 27 functions with the wing members 20 as an effective means for 50 retaining the last members 5 and 7 in their respective extended positions.

From a study of the foregoing description, taken in connection with the accompanying drawings, it is apparent that a last 55 constructed in accordance with my invention embodies certain desirable features which tend to lend rigidity to the structure as a whole, and enable the last sections to be positively held in extended positions. It 60 will be further observed that the construction of the peculiar form of hinge which I employ permits the device, as a whole, to be easily assembled and eliminates, to a degree, a certain amount of accuracy and precision 65 which has heretofore been necessary in the

manufacture of similar lasts, in order that the finished articles might properly function under the various conditions of use to which they are subjected.

What I claim is:

1. In a shoe last, a heel section, a toe section, hinge members pivotally connecting said sections together, one of said members comprising a resilient plate, the other of said members comprising a locking element 75 adapted to assume a locking position upon relative movement of said sections and cooperate with said plate to retain said sections in extended position with respect to each other, the resiliency of said plate being depended upon to retain said locking element in locking position.

2. In a shoe last, a heel section, a toe section, hinge members pivotally connecting said sections together, one of said members comprising a pair of resilient plates, the other of said members comprising a locking element adapted to assume a locking position upon relative movement of said sections and cooperate with said plates to retain said sections in extended position with respect to each other, the resiliency of said plates being depended upon to retain said locking element in locking position.

3. In a shoe last, a heel section, a toe section, hinge members pivotally connecting said sections together, one of said members comprising a resilient plate having a pocket formed therein, the other of said hinge members comprising a locking element adapted to enter said pocket upon relative movement of said sections to lock said sections in extended position, the resiliency of said plate being depended upon to retain said locking element within said pocket.

4. In a shoe last, a heel section, a toe section, hinge members associated with said sections, one of said members comprising a pair of resilient plates having locking element receiving pockets, the other of said members comprising an arm, a locking element carried by said arm, said locking element being adapted to enter one of said pockets to retain said sections in extended positions and to enter the other of said pockets when said sections are moved to collapsed position with respect to each other.

5. In a shoe last, a heel section, a toe section, hinge members associated with said sections, one of said members comprising a pair of resilient plates one of which is provided with a locking element receiving pocket, the other of said members comprising an arm adapted to operate between said plates, and a locking element carried by said arm, said locking element being adapted to enter said pocket to retain said sections in extended position with respect to each other.

6. In a shoe last, a heel section, a toe section, means for hingedly connecting said sec-

tions together, said means comprising pivotally connected hinge members, one of said hinge members being resilient and provided with a pocket and a locking element carried by the other member, said locking element being adapted to enter said pocket to lock the heel and toe sections in extended position with respect to each other, the resiliency of said resilient hinge member being depended upon to retain said locking element in said pocket.

7. In a shoe last, a heel section, a toe section, means for hingedly connecting said sections together, said means comprising hinge members pivotally connected to each other, one of said hinge members being provided with resilient plates having pockets formed therein, a locking element carried by the other of said members, said locking element being adapted to enter one of said pockets to retain said sections in extended position, and to enter the other pocket when said sections are collapsed.

8. In a shoe last, a heel section, a toe section, means for hingedly connecting said sections together, said means comprising a hinge member connected to said heel section, a second hinge member connected to said toe section, the latter named hinge member comprising a resilient plate having a locking element-receiving pocket formed therein, a locking element carried by the first named hinge member, said locking element being adapted to enter said pocket to retain said heel and toe sections in extended position, the resiliency of said plate being depended upon to retain said locking element within said pocket.

9. In a shoe last, a heel section, a toe section, means hingedly connecting said sections together, said means comprising a hinge member carried by said heel section, said hinge member being provided with an arm, a second hinge member carried by said toe section, the latter named hinge member comprising a pair of resilient plates between which said arm is adapted to operate, one of said plates being provided with a locking element receiving pocket, and a locking element carried by said arm, said locking element being adapted to enter said pocket to retain the heel and toe sections in extended positions.

10. In a shoe last, a heel section, a toe section, means for hingedly connecting said sections together, said means comprising a resilient hinge member having pockets formed therein, a second hinge member comprising an arm and a locking ball carried by said arm, said locking ball being adapted to enter one of said pockets to retain said toe and heel sections in extended position and to enter the other of said pockets when said sections are collapsed, the resiliency of said hinge member being de-

pended upon to retain said locking ball within one of said pockets when said toe and heel sections are maintained in extended position.

11. In a shoe last, heel and toe sections, one of said sections being provided with a lug, the other of said sections being provided with a groove adapted to receive said lug, hinge members associated with said sections, one of said members comprising a resilient plate having a pocket formed therein, the other of said hinge members comprising a locking element adapted to enter said pocket to retain said sections in extended position with respect to each other, and a centering pin passed through said lug and said hinge members at their point of pivotal connection.

12. In a shoe last, heel and toe sections, one of said sections being provided with a lug, the other of said sections being provided with a groove adapted to receive said lug, hinge members associated with said sections and pivotally connected together, one of said members comprising a pair of resilient plates one of which is provided with a locking element receiving pocket, the other of said members comprising a locking element adapted to enter said pocket to retain said sections in extended position with respect to each other, and a centering pin passed through said lug and said hinge members at their point of pivotal connection with each other.

13. In a shoe last, heel and toe sections, one of said sections being provided with a lug, the other of said sections being provided with a groove adapted to receive said lug, hinge members connecting said sections together, one of which is resilient and provided with locking element-receiving pockets, the other of said members comprising a locking element adapted to enter one of said pockets when said sections are extended, and further adapted to enter the other of said pockets when said sections are collapsed, the resiliency of said resilient hinge member being depended upon to retain said locking element within one of said pockets when said sections are extended, and a centering and reinforcing pin passed through said lug and hinge members at their point of pivotal connection with each other.

14. In a shoe last, heel and toe sections, one of said sections being provided with a lug, the other of said sections being provided with a groove adapted to receive said lug, hinge members associated with said sections, a tubular element pivotally connecting said hinge members to each other, and a pin passed through said lug and tubular element.

15. In a shoe last, heel and toe sections, one of said sections being provided with an

- 4
- offset portion, the other of said sections being provided with a groove adapted to receive said offset portion, hinge members associated with said sections, one of said hinge members comprising a resilient plate having a locking element receiving pocket, the other of said hinge members comprising an arm, a locking element carried by said arm, said locking element being adapted to enter said pocket to retain said sections in extended position, a tubular element pivotally connecting said hinge members together, and a pin passed through said offset portion and said tubular element.
15. 16. In a shoe last, a heel section, a toe section, means for hingedly connecting said sections together, said means comprising pivotally connected hinge members, one of said hinge members being resilient and provided with locking element-receiving pockets, a locking element carried by the other hinge member, said locking element being adapted to enter one of said pockets to lock the heel and toe sections in extended position, and to enter the other of said openings when said heel and toe sections are collapsed, the resiliency of said resilient hinge member being depended upon to retain said locking element within one of said pockets when said heel and toe sections are maintained in extended position.
17. In a shoe last, a heel section, a toe section, a hinge member in the form of a resilient plate associated with one of said sections, a second hinge member in the form of an arm co-operating with the first mentioned hinge member, one of said hinge members being provided with a locking-element-receiving pocket, and a locking element carried by the other of said hinge
- members adapted to enter said pocket and co-operate therewith to retain said sections in extended positions with respect to each other.
18. In a shoe last, a heel section, a toe section, a hinge member in the form of a resilient plate associated with one of said sections, a second hinge member in the form of an arm co-operating with the first mentioned hinge member, one of said hinge members being provided with a pair of locking-element-receiving pockets, and a locking element carried by the other of said hinge members adapted to enter said pockets when said sections are moved from one position to another with respect to each other.
19. In a shoe last, heel and toe sections, one of said sections being provided with an offset portion, the other of said sections being provided with a groove adapted to receive said offset portion, means for hingedly connecting said sections together, said means comprising pivotally connected hinge members, one of said hinge members comprising a resilient plate, the other of said hinge members comprising a locking element adapted to assume a locking position upon relative movement of said sections and co-operate with said plate to retain said sections in extended position with respect to each other, the resiliency of said plate being depended upon to retain said locking element in locking position and a centering and reinforcing pin passed through said offset portion and hinge members at their point of pivotal connection with each other.

In testimony whereof, I have affixed my signature to this specification.

CLIFFORD KIRBY MacDONALD.
